UNITED STATES PATENT OFFICE.

CHARLES FRANCIS JENKINS, OF WASHINGTON, DISTRICT OF COLUMBIA, ASSIGNOR TO THE GRAPHOSCOPE COMPANY, OF WASHINGTON, DISTRICT OF COLUMBIA, A CORPORATION OF DELAWARE.

MOTION-PICTURE APPARATUS.

1,302,801.

Specification of Letters Patent. Patented May 6, 1919.

Application filed October 17, 1918. Serial No. 128,066.

To all whom it may concern:

Be it known that I, CHARLES FRANCIS JENKINS, a citizen of the United States, and resident of Washington, in the District of Columbia, have invented certain new and useful Improvements in Motion-Picture Apparatus, of which the following is a specification, reference being had therein to the accompanying drawing.

10 The object of this invention is to provide improved automatic means whereby in projecting machines the shutter between the lens and the film will open when the machine is started and brought up to normal speed and will close when the speed falls.

In the accompanying drawings,

Figure 1 is a side elevation of a portion of a projecting machine.

Fig. 2 is a view looking from the right in Fig. 1.

Fig. 3 is a section on the line 3—3, Fig. 1.

Fig. 4 shows the parts seen in Fig. 3 in a different position.

Fig. 5 is a section on the line 5—5, Fig. 3.

Fig. 6 is a perspective view of a member shown in Figs. 3, 4, 5.

In these figures, 1 represents the casing of a projecting machine, 2 a shaft projecting outside the frame and driven, whenever the machine is working, by a pinion 3. On this shaft is mounted a common centrifugal speed governor-like device 4 protected by a casing 5 and carrying at its sliding end a disk 6 which thus moves outward on the shaft when centrifugal force throws the weights 7 outward as shown in Fig. 4. In this sliding, the disk strikes and swings a lever member 8, having suitable shoulders, which is centrally pivoted at 9 upon a lug on the casing. This lever is connected by a link 10 to a crank 11 upon a short bell-crank shaft 11 extending through the casing at some distance above the shaft 2, and the inner arm 12 of the bell-crank is connected by a rod 13 with an arm 14 fixed to a shutter 15 which is pivoted at its upper edge and, when the machine is at rest, prevents light from passing from the lens to the film at the exposure aperture, the parts first described being then in the positions illustrated in Fig. 3. The shaft 11 is

provided with a heavy handle 16 by which, incidentally, the shutter may be manually swung. This handle, when in the position shown in Fig. 1, tends by its weight to hold the shutter tightly closed as it might otherwise open slightly since the disk 6 is not normally pressed against the lever 8. When the centrifugal device on the rapidly rotating shaft slides and the disk by forcing the lever to swing opens the shutter, the handle-weight is swung to the opposite side of the perpendicular where its weight carries the shoulder 17 of the lever out of contact with the disk as in Fig. 4, and holds it there so long as the weights 7 are held in their outer positions. In other words, the disk is never in contact with the lever except momentarily while the shutter is being opened or closed, and hence there is no appreciable wear at this point.

What I claim is:

1. In devices of the class described, the combination with a shutter and automatic devices for opening and closing the same as the operating parts of the apparatus pass from and to a state of rest, of means whereby the shutter is held in either the open or the closed position in which it may be, while said devices are temporarily entirely free therefrom.

2. In apparatus of the class described, the combination with a shaft rotated by the operating force and bearing a centrifugal device, of a light-interrupting shutter, and a pivoted lever connected with the shutter, normally out of contact with the centrifugal device at rest or at operating speed, and arranged to be tilted by said device in passing to or from its position of rest.

3. In apparatus of the class described, the combination with a shaft rotated by the operating force and bearing a centrifugal device, of a light-interrupting shutter, a pivoted lever connected with the shutter, normally out of contact with the centrifugal device at rest or at operating speed, and arranged to be tilted by said device in passing to or from its position of rest, and means resisting the movement of the lever from either limit to which it may be swung.

4. In apparatus of the class described having a shaft rotated by the operating force, and a light interrupting shutter, a pivoted member connected with the shutter to open and close the same by its swinging, a centrifugal device carried by said shaft and arranged to swing said pivoted member to and

fro as its speed rises and falls, and means for holding said member free from the centrifugal device while it is itself holding the 10 shutter open.

In testimony whereof I hereunto affix my signature.

CHARLES FRANCIS JENKINS.
